(57) CLAIM

The ornamental design for a grill oiler, as shown and described.

DESCRIPTION

FIG. 1 is a top perspective view of a grill oiler showing our new design;

FIG. 2 is a front elevational view thereof;

FIG. 3 is a left side elevational view thereof, the right side being a mirror image;

FIG. 4 is rear elevational view thereof;

FIG. 5 is another rear elevational view thereof with the handle and shield shown in dashed lines in FIG. 5 removed;

FIG. 6 is a top plan view thereof; and,

FIG. 7 is a bottom plan view thereof.

The grill oiler is used to oil the grill of a barbecue. The broken lines showing of a handle and shield, and the bristles on the cleaning pad of the grill oiler are for illustrative purposes only; the broken lines form no part of our claimed design.
